(57) **CLAIM**

The ornamental design for a portion of a display panel with a graphical user interface, substantially as shown and described.

DESCRIPTION

FIG. 1 is a front view of a portion of a display panel with a graphical user interface, showing a first embodiment.

FIG. 2 is a front view of a portion of a display panel with a graphical user interface, showing a second embodiment; and,

FIG. 3 is a front view of a portion of a display panel with a graphical user interface, showing a third embodiment.

The broken lines in the display panel illustrate graphical features that form no part of the claimed design.

1 Claim, 3 Drawing Sheets

FIG. 1

FIG. 2

FIG. 3
